GESELLSCHAFT, OF ESSEN-ON-THE-RUHR, GERMANY.

APPARATUS FOR THE ELECTRICAL LONG-DISTANCE CONTROL OF THE VALVE-GEAR OF A HYDRAULIC GUN-POINTING GEAR.

1,375,269.

Specification of Letters Patent. Patented Apr. 19, 1921.

Application filed September 3, 1920. Serial No. 408,070.

To all whom it may concern:

Be it known that I, WALTHER AKEMANN, residing at Essen, Germany, a citizen of the German Republic, have invented a certain 5 new and useful Improvement in Apparatus for the Electrical Long-Distance Control of the Valve-Gear of a Hydraulic Gun-Pointing Gear, of which the following is a specification.

10 This invention relates to such an arrangement for the electrical long distance control of the valve gear of a hydraulic gun pointing gear, which enables a particularly accurate adjustment of the gun barrel to be obtained. A somewhat similar structure is 15 described and illustrated in my co-pending application Sr. No. 408075.

The invention will be described with reference to the accompanying drawings which 20 show an arrangement for the electrical long distance control of the valve gear of a hydraulic gun elevating gear.

Figure 1 is a diagrammatic view, partially in section of the invention.

25 Fig. 2 is a horizontal section through a detail part on a larger scale, looking from below and

Fig. 3 is a section on the line 3—3 of Fig. 2, looking in the direction of the arrow x.

30 A denotes the barrel of a naval gun which is mounted by means of its trunnions a^{12} in a cradle A¹. In order that the elevation can be imparted to the barrel A it is pivotally connected to the piston a^2 of a double 35 acting hydraulic cylinder A³, which cylinder A³ is pivotally mounted at a^{13} and is connected by pipes a^4 and a^5 with electrically controlled cut-off devices B and C which are constructed in the form of valves.

40 It is also connected by pipes d^1 and d^2 , which branch off from the pipes a^4 and a^5 , to a controlling valve D adapted to be operated by hand and which is provided with pipe d^4 for water under pressure and a pipe 45 d^5 for exhausting the water and also with a hand wheel d^3 with which to operate it.

Valves b^1 and c^1 of the cut-off devices B and C are held in their closed positions by springs b^2 and c^2 and can be drawn into their open positions against the pressure of these springs by means of magnet cores b^3 and c^3 , which are rigidly connected to the valves and can be acted on by electrically excitable windings b^4 and c^4 . Pipes b^5 and

c^5 connect the cut-off devices B and C with 55 the casing of a controlling valve adapted for long distance control E, which is provided with a pipe e^1 for admitting water under pressure and a pipe e^2 for exhausting 60 the water.

The movable part of the controlling valve E consists of a piston rod e^6 provided with three controlling pistons e^3 , e^4 and e^5 rigidly mounted thereon and the free end of which terminates in a rack e^7 . Into the rack e^7 65 gears a toothed sector f^1 , which forms part of a gearing, which is contained in a casing F and is shown in Figs. 2 and 3 and which will be more fully described hereinafter. The said gearing is for the purpose of rendering the movements of the piston rod e^6 of the controlling valve E on the one hand dependent on the receiver motor G of an electrical long distance controlling apparatus and on the other hand dependent on the 70 gun barrel A.

The long distance controlling apparatus has a transmitter H (see Fig. 1) which is set up at the observing station and which is constructed in the well known way so that 80 the continuous current supplied to it through conductors h^{10} is transformed into three dephased currents of variable strength. These three dephased currents of variable strength are supplied by a three-phase long 85 distance conductor J to the receiver G, which is constructed as a synchronous motor and receives its continuous current excitation from a local main K. The armature of the transmitter H is rotated by a milled head h^1 and a hand wheel h^2 , which are positively connected to the middle wheels h^3 and h^4 respectively of a sun and planet gear in the manner illustrated in Fig. 1 of the accompanying drawings. The planet wheel h^5 of 90 the gear is mounted on a bent arm on the transmitter shaft h^6 . This rotation of the armature of the transmitter H is transmitted through the conductor J to the armature of the receiver G.

100 The adjusting apparatus, which is adapted to be rotated by the milled head h^1 , is provided with a reading off apparatus h^7 h^8 , which indicates the adjusted range of the target and is used when the transmitter H 105 is to have a rotation imparted to it which corresponds to the range of the target. The adjusting apparatus which is adapted to be

rotated by means of the hand wheel h^2 is positively connected to a sighting telescope h^9 which oscillates about a horizontal axis and is used when it is required to eliminate the influence of an oblique position of the ship (caused for example by pitching or rolling) on the elevation imparted to the gun barrel in respect to a horizontal plane.

The gearing which is adapted to connect the piston rod e^6 of the controlling valve to the receiver motor G and to the gun barrel A and which is substantially inclosed in the casing F is shown in Figs. 2 and 3. The said gearing consists of two worm gears $f^2 f^3$ and $f^4 f^5$ mounted in bearings in the casing F and of which one $f^2 f^3$ is positively connected through a gearing $f^6 f^7$ to the shaft g^1 of the receiver G (see also Fig. 1) and the other through a gearing $f^8 f^9 a^7 a^8 a^9 a^{10} a^{11}$ to the elevating sector a^6 of the gun barrel. The two worm gears are connected by a sun and planet gear $f^{10} f^{11} f^{12}$ with an apparatus, which regulates the stroke of the piston rod e^6 of the controlling valve E and which will hereinafter be termed the stroke apparatus.

This stroke apparatus contains a drum f^{13} carried in bearings and adapted to also rotate with its shaft f^{26} in the casing, the axis of rotation of which drum coincides with the common axis of rotation of the worm wheels f^3 and f^5 and the drum is provided on its outer surface with a rib f^{14} which runs helically. This rib f^{14} being of greater external diameter over the part, which extends over the top half of the length of the drum than that which extends over the other half. The transition from one diameter to the other takes place at a part of the rib marked f^{15} in Fig. 3 and extends over only comparatively short part of the rib f^{14} .

Against the rib f^{14} bears a roller f^{16} which laterally embraces the rib and which is movably mounted on a bolt f^{17} running parallel with the axis of rotation of the drum f^{13} . This bolt f^{17} is fixed on a forked lever arm f^{18} of a double armed lever which is mounted to oscillate on the casing F about an axis, which is likewise parallel with the axis of rotation of the drum f^{13} and the other lever arm f^{19} of which carries on that part of it which projects from the casing the already mentioned toothed sector (f^1) which engages with the rack f^{19} of the piston rod e^6 . The lever arm f^{19} is acted on by a tension spring f^{20} attached to the casing and which tends to rotate the lever f^{18} in such a way that the roller f^{16} bears with pressure against the rib f^{14} .

In addition to the gearing described there is also contained in the casing F a circuit closing apparatus which consists of a movable circuit closing piece together with two fixed circuit closing pieces (f^{21} and f^{24} and f^{25}). The movable circuit closing piece f^{21}

which is constructed as a rubbing brush is attached to an extension of one of the forked arms of the lever $f^{18} f^{19}$ and is connected by a flexible conductor f^{22} to a terminal f^{23} . The two fixed circuit closing pieces f^{24} and f^{25} are arranged in the casing F at such a distance from the circuit closing piece f^{21} , when this latter assumes its central position that contact between the movable and one of the fixed circuit closing devices can only take place when the lever $f^{18} f^{19}$ has rotated through an angle in which the valve rod e^6 has passed over a distance corresponding to the covering of the valve.

The terminal f^{23} is connected by a conductor h^4 (see Fig. 1 also) to the parallel magnet windings b^4 and c^4 and a conductor h^5 with one pole of a bipolar switch K^1 , the other pole of which is connected across a conductor h^6 which branches off into two conductors h^7 and h^8 with the two fixed circuit closing pieces f^{24} and f^{25} . The switch K^1 is for the purpose of establishing connection between the magnet windings b^4 and b^5 of the cut off devices and the local main K , and is for this purpose connected to the main K by conductors h^2 and h^8 .

The switch K^1 is connected by an automatically acting locking device (not shown) with the hand wheel d^3 of the hand operated controlling valve D in such a way that the hand wheel d^3 can only be moved when the switch K^1 is opened. Such automatic locking devices are very common in the art, so that the particular construction of the locking device employed in the present invention need not therefore be more fully described.

In the consideration of the working of the above described arrangement the description thereof will be commenced from the assumption that the gun barrel A has already had an elevation imparted to it which corresponds to a fixed range adjusted on the transmitter H , and that the controlling valve is in its central position and the switch K^1 is in the closed position. Furthermore let it be assumed that the ship takes up a horizontal floating position.

If now the barrel A is to be first brought for the purpose of loading the gun into the horizontal position and afterward into the previous position again, the switch K^1 is brought into the opened position shown in Fig. 1. This causes the circuits leading to the cut off devices B and C to be broken and the cut off devices B and C therefore assume under the action of the springs b^2 and c^2 their closed positions shown in Fig. 1. The hand wheel d^3 of the controlling valve D is now rotated in such a direction that the controlling valve D opens in the desired direction, that is to say, that water under pressure can pass through the pipes d^4 , d^2 and a^5 into the cylinder A^8 . In con-

sequence thereof the piston a^2 and the front part of the gun barrel A rigidly connected thereto moves downward, while the water under pressure displaced by the piston a^2 simultaneously flows through the pipes a^4 and d^1 and also the controlling valve D to the pipe d^5 which carries it away. By means of a return apparatus such as a spring (not shown) the controlling valve D is at the same time returned to its central position, as soon as the gun barrel A has reached the horizontal position.

During the above described movement of the gun barrel A out of the firing position into the loading position the controlling valve E has also passed into a position which deviates from its middle position. Now, as during the movement of the barrel A the toothed sector a^6 has also been moved the shaft f^8 positively connected to the toothed sector a^6 by the gearing f^9 , a^7 , a^8 , a^9 , a^{10} and a^{11} has set the gearing f^4 , f^5 , f^{10} (see Fig. 2) contained in the casing F in motion and thereby effected a displacement of the planet wheel f^{12} and the drum f^{13} connected therewith. On the rotation of the drum f^{13} , which takes place in the opposite direction to that indicated by the arrow y (see Fig. 3) the roller f^{16} is moved on its bolt f^{17} axially downward by the action of the rib f^{14} and passes out of the position shown in Fig. 3 in which it is pressed against the transition from its smaller to its larger diameter denoted by f^{15} (see Fig. 3) into a new position, in which it bears against the part of the rib f^{14} which is of the smaller diameter. The double-armed lever f^{18} , f^{19} is accordingly rotated about its pivot point and passes into a position in which its circuit-closing piece f^{21} touches the fixed circuit-closing f^{24} . The rotation of the lever f^{18} , f^{19} causes in its turn through the medium of the rack gear f^1 , e^7 a movement of the rod e^6 downward, so that the controlling valve E (see Fig. 1) passes into one of its open positions in which the pipe e^1 leading from the pressure reservoir communicates with the pipe b^5 .

The movement of the controlling valve E into its open position does not yet however exert any influences on the gun barrel A, because the circuits for opening the cut-off devices B and C are still broken by the opened switch K^1 and the cut-off devices B and C are in their closed positions in which, even when the controlling valve E is open, no fluid under pressure can pass through to the cylinder A³.

If now after the gun barrel which is in the horizontal position has been loaded, the switch K^1 be closed, then, as when the lever f^{18} , f^{19} is in the position stated, the circuit closing pieces f^{21} and f^{24} touch each other, the circuit K , k^3 , K^1 , k^6 , k^8 , f^{24} , f^{21} , f^{22} , f^{23} , k^4 , b^4 and c^4 , k^5 , K^1 , k^2 , K are closed and the mag-

net coils b^4 and c^4 become supplied with current. The cut-off devices B and C are therefore raised by the corresponding magnets against the pressure of the springs b^2 and c^2 and rapidly pass into their opened positions. Since as has been already stated, the controlling valve E is already opened, water under pressure flows at once from the pipe e^1 through the controlling valve E into the pipe b^5 and thence through the opened cut-off device B and through the pipe a^4 into the cylinder A³, whereat the piston a^2 begins to rise and rotates the gun barrel A in the direction of the elevation of its muzzle, while at the same time the water under pressure displaced in the cylinder A³ by the piston a^2 flows through the pipe a^5 , through the opened cut-off device C, the pipe c^5 and the controlling valve E to the pipe e^2 which carries it away.

The above mentioned rotation of the gun barrel A results in a rotation of the shaft f^{26} and together with it of the drum f^{13} through the medium of the gearing a^6 , a^{11} , a^{10} , a^9 , a^8 , a^7 , f^9 , f^8 , f^4 , f^5 , f^{10} , f^{12} in a direction of rotation which corresponds to the direction of rotation of the arrow y (see Fig. 3). The roller f^{16} accordingly again approaches the rib f^{14} on the drum f^{13} with the transition arc denoted by f^{15} (see Fig. 3) and, as soon as it has again passed out of the position shown in Fig. 3 rotates the lever f^{18} , f^{19} into its central position (likewise shown in Fig. 3) and in which the contact between the circuit-closing piece f^{21} and f^{24} , which still just exists is broken or interrupted and the piston rod e^6 of the controlling valve E is returned to its central position as shown in Fig. 1. The magnet coils b^4 and c^4 are at this time devoid of current, and the cut-off devices B and C very rapidly assume their closed position under the action of the corresponding springs b^2 and c^2 . The admission of water under pressure into the cylinder A³ above mentioned therefore stops as both the controlling valve E and also the cut-off devices B and C are closed, and the gun barrel A therefore remains stationary.

After the gun barrel A has been again run into the position required by the previous position of the transmitter H, a change in the adjustment of the transmitter causes the gun barrel A to assume at once the elevation corresponding to the new adjustment. The operation takes place as follows:

If the milled head h^1 be rotated to correspond to the desired new transmitter adjustment, then the graduated drum h^7 first rotates until the desired range value is opposite the mark h^8 . With the drum h^7 however rotates also the armature of the transmitter H positively connected thereto, and the armature of the receiver G, which is connected by the long distance transmission conductor J, assumes also the corresponding

position. By this means the shaft g^1 and with it the drum f^{13} of the stroke apparatus are set in rotation through the medium of the gearing $f^7 f^8 f^9 f^{11} f^{12} f^{10} f^{26}$. The drum f^{13} is again able to rotate in the direction of the arrow y , (see Fig. 3).

Under the action of the spring f^{20} the roller f^{16} , which hitherto was in contact with the transition arc of the rib f^{14} denoted by f^{15} , slides down over the part of the rib f^{14} which is of smaller diameter, and by this means the lever arm f^{18} passes into such a position that the circuit-closing piece f^{21} mounted thereon approaches the fixed circuit-closing piece f^{24} , while the lever arm f^{18} and the toothed sector f^1 mounted on its lower end cause a movement of the rack e^7 and consequently of the piston rod e^6 of the controlling valve E in the direction in which the controlling valve e^4 begins to permit the admission of the water under pressure from the pipe e^1 into the pipe b^5 . At this moment the circuit-closing pieces f^{21} and f^{24} come into contact with each other, and the circuits which contain the magnet windings b^4 and c^4 are closed. The cut-off devices B and C are therefore raised out of the closed position into the open position.

The water under pressure passes out of the pipe e^1 through the controlling valve E into the pipe b^5 and from this latter through the opened cut-off device B into the pipe a^2 and so into the cylinder A^3 . The piston a^2 consequently rises and imparts an elevation movement to the gun barrel. The water under pressure displaced by the piston a^2 flows away in the manner hereinbefore described. The roller f^{16} of the stroke apparatus has simultaneously passed completely onto the lower portion of the rib f^{14} of the drum f^{13} and consequently the lever $f^{18} f^{19}$ and the piston rod e^6 have moved into their extreme position.

Owing to the rise of the front part A of the gun barrel its rear portion descends with the toothed sector a^6 , which rotation of the toothed sector a^6 causes the drum f^{13} to be rotated in the opposite direction to that indicated by the arrow y through the medium of the gearing which has already been mentioned several times. The drum f^{13} is at the same time returned to the position in which it was situated prior to the commencement of its rotation by the motor shaft g^1 and in which the roller f^{16} assumes the position on the transition arc of the rib f^{14} denoted by f^{15} which is shown in Fig. 3. The lever $f^{18} f^{19}$ consequently also passes back again into its central position, in which position the contact of the circuit-closing pieces f^{21} and f^{24} is interrupted. The magnet coils b^4 and c^4 are thereby rendered devoid of current, so that under the action of the springs b^2 and c^2 the cut-off devices B and C are quickly closed. With the lever $f^{18} f^{19}$,

the piston rod e^6 together with the controlling valve E moves back into the central position, in which the valve port which adjoins the pipe e^1 is completely shut off. This concludes the controlling operation. 70

It is obvious with further explanation that the operation described must take place in exactly the same way when not a raising but a lowering movement of the front part of the gun barrel A is intended. For this purpose it is only necessary to rotate the transmitter shaft h^6 and consequently the armature shaft g^1 of the receiver G in the reverse direction to that in which it was previously rotated. This causes the direction of movement of the other parts concerned to be likewise reversed, and the circuit-closing piece f^{21} is brought into contact with the circuit-closing f^{25} instead of f^{24} . In consequence hereof the ascending piston rod e^6 of the controlling valve E establishes a connection for the water pressure between the pipes e^1 , c^5 and a^5 ; so that the piston a^2 has to descend in the cylinder A^3 . The return of the controlling valve takes place 91 at the same time through the medium of the toothed sector a^6 and the stroke apparatus connected thereto in a manner which corresponds exactly to that in which the operation previously took place, but in the reverse direction of rotation.

It is also obvious without further explanation that the gun barrel A need not be at rest, when the transmitter H and consequently the receiver G is adjusted. 1

No elaborate explanation is needed either as to how the arrangement described works if the assumption that the ship neither rolls nor pitches be allowed to drop. In this case it is only necessary by suitably turning the hand wheel h^2 to point the telescope f^9 horizontally and thus impart to the transmitter H an additional rotation that corresponds to the angle of rolling or pitching of the ship. The gun barrel A must under all circumstances make that movement after the closing of the switch K^1 which corresponds to the adjustment of the transmitter which exists at the particular moment.

Without departing from the spirit of the invention the mechanical connection between the gun barrel A and the shaft f^{26} which carries the drum f^{13} (see Fig. 2) may also be replaced by a synchronous electrical long distance controlling apparatus. By this means a greater independence in the selection of the points at which the casing F and the gearing contained therein are mounted can be secured.

The circuit closing apparatus $f^{21} f^{24} f^{25}$ might also be brought into direct connection with the piston rod e^6 instead of with the lever arm f^{18} .

By suitably arranging the cut-off devices B and C the working of these parts might
